UNITED STATES PATENT OFFICE

154,432

DESIGN FOR A BOX OR THE LIKE

Clarence E. Renander, Lake Ozark, Mo.

Application January 29, 1948, Serial No. 144,121

Term of patent 14 years

(Cl. D58—13)

To all whom it may concern:

Be it known that I, Clarence E. Renander, a citizen of the United States, residing at Lake Ozark, in the county of Miller and State of Missouri, have invented a new, original, and ornamental Design for a Box or the Like, of which the following is a specification, reference being had to the accompanying drawing, forming part thereof.

Fig. 1 is a perspective view of a box or the like, showing my new design.

Fig. 2 is a rear elevation thereof.

Fig. 3 is a side elevation thereof.

I claim:

The ornamental design for a box or the like, substantially as shown.

CLARENCE E. RENANDER.
